UNITED STATES PATENT OFFICE.

WILLIAM MAYO, OF SAN FRANCISCO, CALIFORNIA.

CONTROL FOR SPOT-LIGHTS.

1,334,666.

Specification of Letters Patent. Patented Mar. 23, 1920.

Application filed December 5, 1918. Serial No. 265,434.

To all whom it may concern:

Be it known that I, WILLIAM MAYO, a citizen of the United States, and a resident of the city and county of San Francisco, 5 State of California, have made a new and useful invention—to wit, Improvement in Control for Spot-Lights; and I do hereby declare the following to be a full, clear, concise, and exact description of the same.

10 The present invention is an improved control for spot-lights commonly carried on automobiles, pleasure launches, steamers, and other conveyances.

15 The object of the invention is to provide a convenient means within the pilot house, cockpit or body of the vehicle or conveyance for manipulating an outside spotlight either vertically or horizontally, or both, to throw its glare in the path of the moving convey- 20 ance. A further object is to provide a control for spotlights of such construction that said light will normally be carried in a position in which its rays will be thrown in the path of the moving conveyance, but which 25 may be instantly and easily altered to suit any conditions arising in forward travel. In the structure hereinafter described, the control of both the horizontal and vertical movements is accomplished by handles or 30 levers, both of which are conveniently placed where the pilot or driver may make the aforesaid adjustment.

While the invention is here shown on an automobile, it is equally applicable to the 35 cockpit of a pleasure boat or the pilot house of a steamer, or may be used on wharves, bridges, or other stationary buildings where spotlights are used.

In the accompanying two sheets of draw- 40 ings,

Figure 1 is a fragmentary side elevation of a closed automobile equipped with my improved spotlight control thereon.

Fig. 2 is a cap for covering a portion of 45 the mechanism hereinafter described.

Fig. 3 is a side elevation of an extensible bracket, forming a support and bearing for the working parts of my spotlight control.

Fig. 4 is a plan view of Fig. 3.

50 Fig. 5 is a side elevation of a cap covering the handles or controls of my device, portions being broken away for the purposes of illustration.

Fig. 6 is a section of Fig. 5 taken on the 55 line VI—VI of Fig. 5.

Fig. 7 is a plan view of the working parts

of my control installed on the bracket shown in Figs. 3 and 4.

Fig. 8 is a side elevation of the parts shown in Fig. 7. 60

Fig. 9 is a fragmentary view of the interior of a cap covering the handle of the control showing a lever latch for engaging said handles when in inoperative position.

Referring to the drawings, the numeral 1 65 indicates one of the forward wheels of an automobile of conventional closed body type having a radiator 2, hood 3, cowl 4 and closed body 6. Extending forwardly and obliquely through the cowl 4 as shown at 70 7 is a metal cap 8 which incloses those portions of my mechanism which extend outside the cowl when it is installed. The portions within the closed body of the car are completely housed in a cap 9 through slots 75 in which extend handles which control a lamp 13 mounted outside the body. The working parts of my device are mounted on an extensible bracket composed of two parts 14 and 14^A which are joined together in 80 tongue and groove relation, and slideable to or from each other as may be necessary to meet various conditions in installation. The members 14 and 14^A of the bracket are held together in any desired position by a set 85 85 screw 16 which extends freely through the member 14^A as shown at 17 and is threaded into the member 14 as shown at 18. The members 14 and 14^A have base portions on which are bosses 19 and 21 respectively, 90 which are centrally bored as shown at 22—23 to form bearings for stud shafts 26 and 27. The stud shaft 27 extends upwardly from the base of the bracket 14^A and is provided with a nut 31 threaded on a re- 95 duced portion of the said stud shaft, and a nut 29 at the opposite end of said shaft. The stud shaft 26 is integral with a bracket 33. To the uppermost bifurcated end of bracket 33 are secured two bearings 34 and 100 36 in which are journaled ends of a shaft 37. The cross shaft 37 is provided with a ring 38 between the ends of the bracket 33. The purpose of the ring 38 is to engage the stem 39 of the lamp 13. It will be seen 105 that as the shaft 37 is revoluble in the bearings 34—36, the lamp 13 may be rotated vertically as indicated by the dotted line 41. In order to accomplish this move- 110 ment, I have provided a segmental bevel gear 40 which is rigidly secured to the cross shaft 37. It is necessary to rotate the lamp

13 only through an angle of approximately 90 degrees, therefore the gear 40 is segmental and meshes with a toothed portion of the periphery of a bevel gear 42 which is unfinished through the remainder of said periphery. The shaft 26 is hollow as indicated by the dotted line 43 in order to allow the passage therethrough of an electric light wire 44 which supplies the lamp 13. The bevel gear 42 is rigidly connected to a sprocket wheel 46 which turns freely on the shaft 26. Also on the shaft 26 and fixedly keyed thereto is a sprocket wheel 47.

It will be seen from this construction that 15 when the sprocket wheel 47 is rotated, the entire upper structure including the light 13 is rotated on a horizontal plane and that if the sprocket wheel 47 is held and the sprocket wheel 46 rotated, that the bevel gear 42 by being enmeshed with the segmental gear 40 will rotate the cross shaft 37 and will cause the rotation on a vertical plane of the lamp 13.

The sprocket wheels 46 and 47 are rotated 25 respectively by means of chains 48 and 49 which also pass around sprocket wheels 51 and 52 both of which rotate freely on the shaft 27. The sprocket wheels 51 and 52 are provided respectively with handles 53-54 30 which extend through the housing cap 9 and traverse slots 56-57. The cap 9 is also provided with a slot 58 which permits the assembly of this device by allowing the cap to slip downward over the handles before they are rotated to the position shown in Fig. 7. The sprocket wheels 51 and 52 are provided with anti-friction ball bearings 60-61 which travel in suitable raceways in the boss 21 and in a bearing plate 40 62. The bearing plate 62 is held in place by washer 63 secured by nut 29. In order that the weight of the lamp 13 may not cause the rotation of the sprocket within the housing, I have provided a latch 65 which is pivotally secured to the outside of the cap 9 as 45 shown at 66. The latch 65 is provided with a slot 67 through which extends the pin 68 which limits the vertical movement of the latch 65. The said latch 65 is normally held 50 upward by a wire spring 69, one end of which is engaged in a hole 71 in the end cap 9; the opposite end bears, as shown at 72, against the lower end of the latch. The latch 65 is provided with two semi-circular 55 notches 73 and 74 for engaging the handles 53 and 54 and is also provided with a thumb engaging portion 76. This structure makes

it possible for a driver to reach with one hand and operate the levers 53 and 54 and release the latch 76 with the thumb of the 60 same hand, giving control of the lamp 13 in both horizontal and vertical planes, while steering with the other hand.

This device is of special value on limousines and closed body types of automobiles. 65 When used on automobiles, it is more often necessary to rotate the lamp 13 on a horizontal plane than on the vertical, as in ordinary travel when once set vertically at the proper distance ahead of the vehicle, it may 70 be left in that position and rotated horizontally to light curves and objects in the roadway.

By tightening the nuts 29 and 31 a frictional engagement may be maintained between the sprocket wheels 51 and 52 which is sufficient to hold the vertical rotating means in the same relative position to the horizontal means. 75

Having thus described this invention, 80 what I claim and desire to secure by Letters Patent is:

A spot light control comprising a base, 85 said base being formed of two sections slideable one upon the other and held in adjusted position by a bolt, bosses upon each of said base sections, a shaft mounted upon one of said bosses, sprocket wheels mounted upon said shaft, a cover for said sprocket wheels, a handle attached to each of said 90 sprocket wheels and adapted to impart rotation to either wheel independently, a latch attached to said cover and adapted to engage said handles, a shaft mounted upon the boss carried by the opposite section of said 95 base, sprocket wheels mounted upon said shaft and having flexible connection with said first mentioned sprocket wheels, a gear carried by the upper of said last mentioned 100 sprocket wheels, a vertical bracket, a lamp carried by said bracket, trunnions carried by said bracket, said lamp being rotatable on said trunnions, a segmental gear connected to said bracket in mesh with said gear and said bracket being connected to the 105 lower of said last mentioned sprocket wheels.

In testimony whereof, I have hereunto set my hand at San Francisco, California, this 14th day of November, 1918.

WILLIAM MAYO.

In presence of—
A. J. HENRY.
